CLAIM

The ornamental design for a child seat backrest, as shown and described.

DESCRIPTION

FIG. 1 is a front view of an embodiment of a child seat backrest according to the present invention.

FIG. 2 is a back view of the embodiment of the child seat backrest of FIG. 1.

FIG. 3 is a top view of the embodiment of the child seat backrest of FIG. 1.

FIG. 4 is a bottom view of the embodiment of the child seat backrest of FIG. 1.

FIG. 5 is a right side view of the embodiment of the child seat backrest of FIG. 1.

FIG. 6 is a left perspective view of the embodiment of the child seat backrest of FIG. 1.

FIG. 7 is a back perspective view of the embodiment of the child seat backrest of FIG. 1.

FIG. 8 is a left perspective view of the embodiment of the child seat backrest of FIG. 1, shown with seatbelt latches in an extended orientation.

FIG. 9 is a left side view of the embodiment of the child seat backrest of FIG. 1, shown installed in a dashed car seat with a dashed child secured therein by belts.

The dashed lines in FIG. 1 illustrate a seatbelt, and form no part of the claimed design. The dashed lines in FIG. 9 illustrate a car seat, child, child seat backrest belts, and car seatbelt, and form no part of the claimed design.
